WALTER W. FOSTER, OF WICHITA FALLS, TEXAS

COMBINATION MAKE-UP CATHEAD AND FRICTION HOIST

Application filed May 23, 1927. Serial No. 193,542.

This invention relates to rotary well drilling equipment, and it refers more particularly to a combination make-up cat head and friction hoist and the principal object of the invention resides in the provision of a novel improvement in friction hoists, associated with a cable assemblage, by which the manual labor usually necessary in making up a casing assembly is reduced to the very minimum.

Another object of the invention resides in the provision of a weight member so co-operating with the said friction hoist drum as to return the cable assembly to normal position after each operation of spinning in a joint of casing, and which usually is accomplished manually.

Still another object of the invention resides in the provision of an assembly such as designated, in which the friction hoist is capable of performing any of the duties ordinarily performed by the regular cat head, which is customarily used on the end of the line shaft, such for example as spinning and tonging up casing, and making any horizontal pull or vertical lift of which the ordinary cat head is capable, yet without the dangers and cumbrousness usually present in this method of operating the lines.

With these primary objects and advantages in view, the invention has particular reference to certain salient features of construction and operation of parts by which said objects are attained and which will become manifest as the description proceeds, taken in connection with the accompanying drawings, wherein:

Figure 1 represents a perspective view of a cat-head constructed according to the invention.

Figure 2 is an axial cross-sectional view of the cat-head.

Figure 3 is a fragmentary view of the clutch mechanism and other related parts.

Figure 4 is a fragmentary view of an ordinary well derrick, showing the complete invention thereon in operative position.

Figure 5 is a detail view of the weight operating with the cable assembly.

Figure 6 is an end view of the weight, and

Figure 7 represents a sectional view of the cable illustrating the manner of inserting a spider to establish a lug in the length thereof.

Speed in making up and breaking out casing is of course the most important factor in present day drilling, and it has been found that the most expeditious way this can be accomplished is by winding a manila rope several times about a joint of casing and manually pulling the latter to spin the same into the preceding casing joint. Two or more workmen are required to set up casing in this manner and the work is very strenuous. The present invention proposes to accomplish in a more expeditious manner mechanically that which has previously been done manually, with a considerable reduction in time and effort.

Continuing now more in detail with the drawings, reference is primarily made to Figures 1 to 3 inclusive, showing the preferred construction of drum or cat-head forming a component part of the invention. The invention consists primarily of a flange 1, fixed by key 2 upon the draw works line shaft 3, which latter, as apparent in Figure 4 likewise carries the drilling drum 4, the latter however being apart from the invention. Surrounding the flange bushing 5 is a bushing 6 of bronze or an equivalent material, and surrounding this is a bushing 7 integral with the cam 8, and bracket 9 which latter is bolted at *a* to the draw works post 10, supporting one end of the shaft 3. The shaft 3 is constantly rotating during the operation of setting up casing, and since the flange 1 is fixed thereto it also is constantly in motion while the elements of the drum consisting of the bracket bushing 7, cam 8 and outer shell 11 are freely mounted upon the flange bushing 5 and not rotated except when thrown into frictional engagement with the flange 1, as will be presently described. The intermediate bronze bushing 6 is adapted to minimize friction between the flange bushing and stationary bracket bushing 7 and prevent "freezing."

Co-operating with the cam 8 is another cam 12, constructed to conform in the manner illustrated in Figure 3 and has attached thereto a lever 13, actuation of which causes the outer shell to move outward or toward the end of the shaft 3, whereby frictional contact will be made by the flange of the outer shell 11 against the annular clutch surface 14 affixed to the inside of the flange 1. The outer shell 11 is provided with a babbitt bearing surface 15 by which frictional wear is further averted.

Intermediate the cam 12 and flange 11 is a bearing race 16 to prevent wear upon the latter by said cam 12 when the same is operated by the lever 13 to urge the shell 11 outward as described above.

Referring now particularly to Figure 1, the means provided for arresting motion of the outer shell 11 when friction of the clutch 14 is relieved, consists of an arm 17, pivotally supporting at its either end a brake shoe 18, each of which are frictionally engageable with an annular surface *b* on each flange of the outer shell 11. The arm 17 has protruding therefrom an integral lever 19, pivotally supported at a central position by an arm 20 affixed to the bracket 9 on the post 10 and to the free end of the lever 19 is attached a rod 21 depending to the derrick floor 22 at which point it is attached to a foot pedal 23. The rod is provided with a joint 24 to enable it to be adjusted as to length.

An upward pull upon the lever 13 will obviously urge the outer shell 11 of the drum outward into frictional engagement with the clutch surface 14 affixed to the flange 1, by reason of the co-operative action of the cams 12 and 8, and the outer shell 11 being otherwise free to rotate is carried around by the constantly rotating flange 1 affixed to the shaft 3. The cable 25 wound about the outer shell 11 is operated thereby as will be presently described. Upon release of the lever 13, the outer shell 11 will recede from its frictional contact with the clutch band 14 to be independent, and at this time, the pedal 23 is depressed to bring the brake shoes 18 into engagement with the surface *b* of the outer shell 11 to control the latter and to hold the cable in the position to which it has been moved, unless, of course, strain on the cable has been relieved.

A fragmentary representation of a derrick is shown in Figure 4, showing also a partial view of the draw works, in which the usual cat head is supplemented by the friction hoist embodying the invention, upon the end of the draw works shaft 3.

The cable 25 surrounding the drum embodying the invention extends upwardly and over a crown block, (not shown), and downwardly to where it is removably connected to a weight member 26, illustrated in detail in

Figures 5 and 6, and shown in operative position in Figure 4.

It will be noted that a lug is applied to the cable 25 at a suitable position in its length, in the manner shown in Figure 7, which consists in placing a spider 27 between the strands of the cable 25, sliding the cone 28 thereover and pouring babbitt therein to firmly weld the same to the cable. The weight member 26 is constructed with protruding arms 29 in which opposing recesses are provided to conformably receive the cone member 28, and a similar member 30, applied to the end of a rope 31 is received in the other recess. The recesses in which these members 28 and 30 are received are slotted at *c* as shown in Figure 5 so as to enable the cables to be released therefrom with a minimum of effort by simply unseating the members and drawing the cables through the slots *c*.

Acting as a supporting means and guide for the weight member 26 is a cable 32, secured to the derrick leg at a suitable distance above the floor, and having its other end attached to an eye 33 integral with a bracket 34 affixed by U clamps 35 also to the derrick leg. A sheave 36 is carried by the bracket 34, and the position of the latter directs the sheave toward the rotary table 37, the point of operation.

In order to better accomplish horizontal pulls in more than one direction, the brackets 34 is provided with a hinged connection with the U clamp 35 surrounding the derrick leg, enabling it to be swung to various angles with respect to its support.

The rope 31 is, as stated previously, connected to the weight member 26 and passing about the sheave 36, is wound a number of times about the casing section 38.

In practical operation the parts of the invention are arranged in the manner illustrated in Figure 4. An end of the cable 25 suitably affixed to the outer shell 11 of the assembly and wound about the same a number of times, is directed upwardly through guide sheave 28^a and over the conventional crown block and downwardly to the derrick floor. Usually a greater amount of this cable is employed than is necessary in spinning in easing sections in making up an assembly, but by applying a hook 39 on the end of the cable it makes a very efficient and practical hoisting apparatus for bringing in heavy and unwieldy objects from the yard, the feature of frictional control and ready braking facilities of the drum playing a very important part in the performance of the invention in this regard.

On the other hand, in adapting the invention in setting up a casing assembly, the cone shaped member 28, affixed on the cable 25 is mounted in the upper recess in the member 26, and the rope 31 wound a few times about the casing section held in readiness for spin-

ning in. The lever 13 of the drum is pulled upwardly by an attendant, while another operator holds the free end of the rope 31. Operation of the lever urges the outer shell 11 of the drum outward to effect rotation of the latter, consequently winding up the cable, pulling the weight member 26 upward along the guide cable 32, and spinning the section of casing 38 into the joint 40.

5 10 It is necessary only to release the lever 13 to permit free movement of the outer shell 11 of the assembly to again lower the cable to operative position, since the weight member 26 is constructed as to be sufficiently heavy 15 as to unwind the cable 25 from the drum when released from the friction engagement with the driving flange 1. Downward movement of the weight member 26 is controlled by the brake shoes 18 controlled in turn by 20 the foot pedal 23.

Manifestly, the construction shown is capable of considerable modification and such modification as is in keeping with the appended claims is also considered within the 25 spirit of the invention.

What is claimed is:

1. In a combination make-up cat-head and friction hoist including in combination with a rotating shaft, the same comprising a member 30 fixed to the shaft to rotate therewith and having a flange, an outer shell freely mounted on said fixed member having flanges, one of which is arranged for frictional engagement with the flange of said fixed member; means to actuate said outer shell to effect such frictional engagement, and means 35 capable of being brought into frictional engagement with the inner surfaces of said shell flanges to arrest rotation of said outer shell when the frictional engagement of said flanges is released.

2. In a combination make-up cat-head and friction hoist including with a rotating shaft, a flanged member rotating therewith and a 45 flanged outer shell freely mounted on said flanged member; means for actuating said outer shell to bring its flange into frictional contact with said flanged member to cause said outer shell to rotate with said rotating shaft and flanged member, and means capable of being urged into frictional contact with either flange of said outer shell to arrest its rotation upon release of said shell actuating means.

55 3. In a combination make up cat-head and friction hoist; a flanged member fixed on a rotating shaft, and an outer shell member freely mounted on said flanged member, and capable of movement longitudinally on said latter member as to bring one of its flanges into frictional engagement with the flange of said flanged member to cause said outer shell to move with said flanged member and shaft, means to effect such movement and 60 means capable of movement into frictional 65

contact with both flanges of said shell member to arrest its rotative motion upon release of the frictional engagement between said flanged member and outer shell.

In testimony whereof I affix my signature. 70
WALTER W. FOSTER.
